REEL FOR RIBBON TYPE MATERIAL

Arnold P. Hultgren, River Forest, Ill., assignor to American Molded Products Co., Chicago, Ill., a corporation of Illinois

Filed Apr. 21, 1958, Ser. No. 50,544

Term of patent 14 years

(Cl. D26—14)

FIGURE 1 is a face view of a reel for ribbon type material, showing my new design.

FIGURE 2 is an edge view of the reel of FIGURE 1.

FIGURE 3 is a cross sectional view on an enlarged scale, taken as indicated by the line 3—3 on FIGURE 1.

FIGURES 4, 5, 6 and 7 are enlarged fragmentary detail views taken as indicated by the lines 4—4, 5—5, 6—6 and 7—7, respectively, on FIGURE 1.

I claim:

The ornamental design for a reel for ribbon type material, substantially as shown.
